UNITED STATES PATENT OFFICE

HERMAN KLEIN, OF CHICAGO, ILLINOIS

CURTAIN RAISING DEVICE

Application filed October 22, 1930. Serial No. 490,386.

My invention relates in general to an improved device for raising a window curtain, and more particularly to a device for attachment to the upper ledge of the lower sash 5 of the window, to raise the curtain as the sash is raised so that the lower edge of the curtain remains approximately even with the lower edge of the sash.

The principal object of my present invention is to provide means for keeping the lower edge of the curtain substantially even with the lower edge of the window as the window is raised, to prevent soiling and damaging of the curtain as a result of the curtain blowing 15 against the screen, or window casing when the window is opened.

Another object is to provide a simple, sturdy device for this purpose, which may be easy and inexpensive to manufacture.

20 Another object is to obtain these results without injuring the curtain in any manner, by wrinkling, kinking, or tearing in the place at which the curtain is held by my device.

Another object is to provide extension 25 means in my device so that the curtain gripping means may be moved in a horizontal plane in position to correspond with the distance from the window at which the curtain is hung.

30 Other objects and advantages of the invention will be apparent from a consideration of the following detailed description taken with the accompanying drawings, wherein,

Fig. 1 is a front elevation of a window with 35 the curtain in place in my device,

Fig. 2 is a sectional view taken on line 1—1 of Fig. 1 of the window with the lower sash raised, the curtain raising device of my invention being attached to the upper edge of 40 the lower sash of the window curtain in the position it assumes when held by my device as the window is raised,

Fig. 3 is a perspective view of the preferred 45 form of my device, as shown attached to the window in Fig. 2,

Fig. 4 is a side elevation of a modification of 50 my device pivotally secured to the upper ledge of the lower sash, in such a way that it may be swung back over the window ledge when

Fig. 5 is a front view with the curtain in section, of another modification, in which the upper arm is movable in a vertical plane,

Fig. 6 is a side elevation of the same showing the upper arm resting on the curtain which in turn is pressed against the lower arm or brush, 55

Fig. 7 is a fragmentary plan view of my device as constructed to fasten to the center of the upper ledge of the lower sash of the window so as to engage with the inner edge 60 of the curtains where a double curtain is used,

Fig. 8 is a side elevation of the same in position to engage the curtain for raising with 65 the sash, and

Fig. 9 is a fragmentary side elevation showing position of the hinge and fragment of supporting arm when the latter is hanging down when not in use, 70

Referring now to the drawings, my device is fastened to the upper ledge of the lower sash of the window by means of screws through a bracket 2. Support 3 integral with the bracket and extending at right angles thereto, is a flat metal piece with edges turned inwardly in the form of channels 6. In order that my curtain raising device may be adapted to any variation of the distance from the curtain to the window, I provide an extension 7 of the same construction as the outer metal piece 3, with metal rod 4 and shank 8 of brush 5 rigidly secured in the channels of extension 7, the whole slidably encased in the outer support 3. 80

In the use of my curtain raising device the window curtain 10 hangs from any ordinary curtain rod 9. With the window closed and the lower edge of the curtain hanging substantially even with the lower edge of the 90 lower sash, each edge is held in a device 14 and 16. As the lower sash is raised to a position as shown in Fig. 2, the curtain 10 held on the bristles of the brush 5 is raised with the sash, the lower edge remaining in the 95 same position relative to the lower edge 13 of the sash as when the window is closed. With the rod 4 to the rear of the brush as shown in Fig. 2 the curtain drapes as at 11, inside the curtain proper. The curtain so 100

suspended presents a neat and even appearance, and there is no possibility that the lower edges will blow against the screen, against the window casing, or against the outside of the building, should the screen be removed. Not only will the curtain become soiled should this occur, but may also be torn and damaged.

The metal rod 4 may be either in front of the brush 5 as in Fig. 4, or to the rear, as in Fig. 2. The edge of the curtain is inserted in the same manner in each case, that is, under the rod and over the brush, but with the rod to the rear the curtain drapes in back of the lower portion, while with the rod in front the reverse is true.

It would be convenient at times to swing the curtain raising device back over the window ledge and out of the way. For this purpose I provide the metal support 3' made up in the manner above described integral with a U-shaped bracket 17 as shown in Fig. 4. Bracket 17 is pivotally secured to the U-shaped portion of bracket 19 by means of a pin 18 through holes in the upper and lower arms of brackets 17 and 19. Bracket 19 is secured in turn to the upper ledge of the window sash by means of screws 20 through the lower portion of the bracket. This entire mounting is above the upper ledge of the lower sash of the window so that the device may be swung back over the ledge when not in use.

If one does not care to have the curtain looped under the metal rod 4 and over the brush 5 as shown in Fig. 2, I provide a modification, as shown in Figs. 5 and 6, whereby a metal rod 21 is rotatably secured in a groove 22 of support 23 of the same construction as the metal piece 3. The rod 21 moves in a vertical plane slightly inside the center of the brush and parallel thereto. The shank of the brush 5^b is rigidly secured in the lower channel 24 of the support 23, the latter being at right angles to the brush and at an angle of about 60° with the horizontal as shown in Fig. 5. The device can be secured to the window sash in either of the ways shown in Figs. 2 and 4. The window curtain 10 then hangs over the outer face of the brush. As rod 21 is dropped from a vertical to a horizontal position, the weight of the rod holds the curtain against the brush so that the bristles will grasp it slightly and hold the curtain in that position as the lower sash is raised. The curtain will then drape to the inside as the sash is raised with the lower edge of the curtain remaining in the same position as shown in Figs. 1 and 2.

If a double curtain is used, it is necessary to engage the inner edges of these curtains as well as the outer edges. For this purpose I provide my curtain raising device with laterally extending arms as shown in Fig. 7. The construction is substantially the same as that shown in Fig. 3, with supporting arm 3^b chan-

neled along its edges so that extension 7^b will slide therein. Brushes 5^c and 5^d together with rods 4^b and 4^c, are rigidly secured to extension means 7^b, vertically displaced from one another as shown in Fig. 8. This embodiment of my invention is secured to the center portion of the upper ledge of the lower sash of the window by means of screws 26 through the bracket 27 of the hinge 28. The hinge 28 consists of the two U-shaped sections 29 and 31, the latter integral with supporting arms 3^b of my device, and the former a part of bracket 27. They are hingedly connected by pin 32. With my device in position as shown in Fig. 8 for engaging the edge of the curtain and raising or lowering the same as the sash is moved up or down, the flange 33 of the section 31 is supported by section 29 behind flange 34 of the same. With my device in this position pin 32 is rearwardly in the longitudinal slot 36, the latter in a horizontal direction. When my device is not in use it may be dropped down parallel with the window. This is accomplished by raising arm 3^b so that flange 33 clears flange 34, and then pulling the arm forward so that pin 32 is to the front of slot 36. Flange 33 will then drop down below flange 34 as shown in Fig. 9, and my device will hang in a vertical position.

The brush 5 which I have employed successfully in my curtain raising device is the type ordinarily used in cleaning the inside of small test tubes. The object is to have a brush with fairly stiff bristles which will pierce the curtain slightly but present a resilient surface for the curtain to drape over as it is raised in conjunction with the lower sash.

The embodiments of the invention described are only practical and convenient forms of the invention and it will be understood that other modifications could be made therein without departing from the spirit and scope of the invention.

What I claim is new and desire to protect by Letters Patent of the United States is:—

1. In a device for moving a curtain with a window sash, a forwardly extending arm secured to said sash, and laterally extending arms carried by said forwardly extending arm to engage a portion of the curtain and move it with the sash.

2. In a device for moving a curtain with a window sash, a forwardly extending arm, a laterally extending arm secured thereto provided with bristles for engaging the curtain, and means for holding the curtain in engagement with the bristles.

3. In a device of the class described, a bracket for attachment to a window sash, an arm forwardly extending from said bracket, laterally extending arms secured to said forwardly extending arm, with said laterally extending arms in a position whereby the

curtain passing between the arms is engaged by said arms, and moved with the sash.

4. In a device for moving a curtain with a window sash, a bracket for attachment to the window sash, a forwardly extending arm pivotally connected with said bracket, extensible means in said forwardly extending arm, laterally extending arms secured to said extensible means in the forwardly extending arm, and in a position one above the other and vertically displaced therefrom, whereby the weight of the curtain passing between the arms causes the arms to frictionally hold the curtain.

15 5. In a device for moving a curtain with a window sash, a forwardly extending arm secured to said sash, laterally extending arms secured to said forwardly extending arm, one of said laterally extending arms being above the other, the lower arm being rigidly secured, and the upper arm rotatably secured so as to be raised and lowered to permit insertion and removal of the curtain, and whereby said arm when lowered, holds the curtain in engagement with the lower arm, and said curtain is raised and lowered with the sash.

6. In a device for moving a curtain with a window sash, a support attachable to the window sash, a laterally extending arm carried by said support, said arm having bristles thereon, the ends of which form an arcuate surface, and means for holding the curtain in engagement with said arcuate surface.

7. In a device for moving a curtain with a window sash, a bracket for attachment to the sash, an arm extending from said bracket and hingedly connected therewith, said hinge comprising means for holding the arm in operating position, laterally extending arms carried by said first arm and means on said laterally extending arms for engaging the curtain and moving it with the sash.

8. In a device for moving a curtain with a window sash, a bracket for attachment to the sash, an arm extending from said bracket and hingedly connected therewith, said hinge comprising two U-shaped sections with engaging projections which hold the arm in supporting position, and means for disengaging the projections to allow the arm to drop in an idle position, and means carried by said arm for engaging the edge of the curtain to move it with the sash.

9. In a device for moving a curtain with a window sash, independent supports adapted to be secured to the lower window sash, a forwardly extending arm secured to each of said supports, each arm having independent laterally extending means for engaging opposite faces of a side edge of the curtain whereby the curtain is moved with the sash.

In witness whereof, I hereunto subscribe my name this 6 day of Oct., 1930.

HERMAN KLEIN.
